CLAIM

The ornamental design of a ventilated waste can with side opening, as shown and described.

DESCRIPTION

FIG. 1 is a front perspective view of the ventilated waste can with side opening according to the inventive design;
FIG. 2 is a front elevation view thereof;
FIG. 3 is a back elevation view thereof;
FIG. 4 is a side elevation view thereof, the opposite side being a mirror image;
FIG. 4 is a top plan view thereof;
FIG. 5 is a bottom plan view thereof;
FIG. 7 is a front perspective view of the design, with an unornamented top;
FIG. 8 is a front elevation view thereof;
FIG. 9 is a back elevation view thereof;
FIG. 10 is a side elevation view thereof, the opposite side being a mirror image;
FIG. 11 is a top plan view thereof; and,
FIG. 12 is a bottom plan view thereof.
